UNITED STATES PATENT OFFICE.

OLIVIER PIETTE, OF BRUSSELS, BELGIUM.

COKE OVEN.

Application filed April 7, 1921. Serial No. 459,439.

To all whom it may concern:

Be it known that I, OLIVIER PIETTE, a subject of the King of Belgium, and resident of Brussels, in the Kingdom of Belgium, have

- 5 invented certain new and useful Improvements in and Relating to Coke Ovens; and I do hereby declare the following to be a full, clear, and exact description of the invention, such as will enable others skilled 10 in the art to which it appertains to make and use the same, reference being had to the accompanying drawings, and to letters or figures of reference marked therein which form a part of this specification.
- 15 In a coke oven of the type described in the U. S. Patent 1,370,481 delivered on the first of March 1921, the combustion of the gas is produced at the base of the vertical flues of the lateral walls divided relatively 20 to their transverse axes into two parts delimiting portions of equal capacity in the carbonization chambers.

The gases in combustion in the flues of one half of the lateral wall, rise in each vertical flue, unite together in the horizontal channel passing above the said flues and descend through the flues of the other half of the lateral wall in order to penetrate afterwards in the regenerators through the intermediary 30 of a flue of the hearth which extends over half the oven.

The reversing of the current of fluids is periodically effected.

In order to effect an economical heating 35 in the said ovens, it is advantageous to send to the chimney products of combustion containing a small percentage of free oxygen only.

It is, however, necessary for various 40 reasons to send into the vertical flues of the oven, a quantity of air much larger than the theoretical quantity. Indeed the gases from the coke oven which are burned in the flues with a quantity of hot air giving a 45 theoretical combustion would produce a temperature of combustion which would cause the melting of the bricks of the lateral walls. Moreover, it is advantageous to limit the length of the flames which rise in the flues 50 in order to avoid too high a temperature of the upper part of the charge and to prevent thus the decomposition of certain by-products.

It is not practical to carry out the theoretical combustion in the flues with rising 55 flames, it is rational to make a judicious

choice of means allowing of avoiding the drawbacks above-mentioned by an appreciable excess of hot air, a primary rapid combustion of the gases admitted to the base 60 of the upward flues, and to make use of the said excess of air for causing, together with the supplementary quantity of gas admitted in a suitable region, a secondary combustion giving products of combustion approximate- 65 ly corresponding to the theoretical combustion.

The object of the present invention is to obtain in ovens of the kind above-mentioned the combination in each lateral wall, on the 70 one hand of a primary admission of gas at the base of the vertical flues situated on one side of the axis of the battery and receiving a certain excess of hot air, and on the other hand, an arrangement of one or 75 several secondary gas admissions in that part of the horizontal collector of the lateral wall which is situated on the other side of the axis of the battery, for the purpose of effecting in the said part of the collecting 80 channel, a mixture of the said additional quantity of gas with the products of combustion having a small combustible power, and to obtain a second slow combustion 85 which will be achieved in the gases descending in the heating flues on this side of the furnace in order to give products of combustion free from any harmful excess of air.

The above system is essentially different from the various other systems of similar 90 ovens in which gas admissions have been provided at the upper part and the lower part of the vertical flues.

The accompanying drawings illustrate 95 diagrammatically and by way of example a mode of construction of an oven according to the present invention.

Figs. 1 and 2 are two identical transverse sections during two different periods of working.

In the following description reference numerals with a dash are used for the elements of construction similar to those represented by the numerals without dashes but situated on the opposite side of the axis 105 of the battery.

Fig. 1 shows a working period in which the total admission of the air necessary for the combustion 5 and the primary admission of gas 1 are effected at the base of each of 110 the flues arranged on the left side of the axis of the battery, and the products of the

combustion unite together in the horizontal collecting flue 3 in order to pass on the other side of the axis of the battery into the flue 3'. One or several secondary gas admissions 5 4' are arranged in the said flue 3', and are adjusted in such a manner as to give a quantity of gas which is proportional to the quantity of oxygen which is found in the products of combustion passing on this side 10 of the axis of the battery.

In the flue 3', the said supplementary quantity of gas is progressively mixed with the products of combustion at a high temperature but of a small combustible power 15 and cause the beginning of a secondary combustion which will be achieved in the flues 2' and will give products of combustion which will be almost free from oxygen which products leave through openings 5' into the 20 flues of the right hearth and afterwards into the regenerators placed on this side.

Fig. 2 shows a period of working after the draught has been reversed. The total admission of air is effected through the openings 5', and the primary admission of gas is effected through openings 1' situated at the base of the flues 2', arranged on the right side of the axis of the battery. The products of the combustion unite in the horizontal 30 collecting flue 3', and pass to the other side of the axis of the battery into the flue 3. By means of one or several secondary gas admissions 4 arranged in the said flue, a quantity of gas is admitted which is proportional 35 to the quantity of oxygen which is found in the products of combustion pass-

ing on this side of the axis of the battery. The said products of combustion are progressively mixed in the flue 3 with a supplementary quantity of gas which is admitted 40 and a second combustion is started which will be achieved in the flues 2 in order to give products of combustion almost free from oxygen and leaving through openings 5 into the flue on the left hand side of the 45 hearth, passing afterwards into the regenerators placed on the other side.

What I claim is:

A regenerative horizontal coke oven having vertical heating flues and a horizontal collector above said vertical flues and with which the latter communicate at their upper ends, said oven comprising means at the base of the vertical flues on each side of the axis of said oven for the admission of 50 gas and a quantity of heated air in excess of that required for the combustion of said gas and means for admission of additional gas into the part of said horizontal collector on each side of said axis, whereby, when 55 gas and air are admitted to the flues on one side of said axis, additional gas may be admitted to the part of said horizontal collector above the vertical flues on the other side of said axis, and vice versa. 60 65

In testimony whereof I affix my signature in presence of two witnesses.

OLIVIER PIETTE.
